(57) **CLAIM**

The ornamental design for thin flatware eating utensils, as shown and described.

DESCRIPTION

FIG. 1 is a top view of one eating utensil of the present invention representing a fork with one end thereof illustrated using spaced apart broken lines;

FIG. 2 is a side view of the fork shown in FIG. 1 with one end thereof illustrated using spaced apart broken lines. The opposite side view is a mirror image thereof;

FIG. 3 is a bottom view of the fork shown in FIG. 2 with one end thereof illustrated using spaced apart broken lines;

FIG. 4 is a perspective view of the fork shown in FIG. 1 with one end thereof illustrated using spaced apart broken lines;

FIG. 5 is a top view of the another eating utensil of the present invention representing a spoon with one end thereof illustrated using spaced apart broken lines;

FIG. 6 is a side view of the spoon shown in FIG. 5 with one end thereof illustrated using spaced apart broken lines. The opposite side view is a mirror image thereof;

FIG. 7 is a bottom view of the spoon shown in FIG. 6 with one end thereof illustrated using spaced apart broken lines; and,

FIG. 8 is a perspective view of the spoon shown in FIG. 5 with one end thereof illustrated using spaced apart broken lines.

The broken dotted lines which define the bounds of the claimed design form no part thereof.
